(57) **CLAIM**

The ornamental design for a vehicle tire tread, as shown and described.

DESCRIPTION

FIG. 1 is a perspective view of a vehicle tire showing my new tire tread design, it being understood that the depicted tread pattern extends over the entire circumference of the tire;

FIG. 2 is an outside elevational view thereof;

FIG. 3 is an inside elevational view thereof;

FIG. 4 is a rear elevational view thereof; and,

FIG. 5 is an enlarged fragmentary view thereof.

In the drawing figures, the tire features shown in broken lines indicate environmental subject matter only, and form no part of the claimed design.
